UNITED STATES PATENT OFFICE

LEONARD CHAIN, OF OWENSDALE, PENNSYLVANIA

KNOCKDOWN BOX

Application filed June 9, 1931. Serial No. 543,219.

The present invention relates to a knock down box particularly intended for shipping purposes and has for one of its important objects to provide, in a manner as hereinafter set forth, a device of this character which is formed of metal and which comprises a novel construction, combination and arrangement of parts whereby the same will occupy a minimum of space when disassembled.

Another important object of the invention is to provide a box of the character described which will be simple in construction, strong, durable, reliable in use, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:—

Figure 1 is a view in top perspective of a box constructed in accordance with this invention showing the same assembled.

Figure 2 is a view in horizontal cross section through the assembled box.

Figure 3 is a vertical sectional view taken substantially on the line 3—3 of Figure 2.

Figure 4 is a vertical sectional view taken substantially on the line 4—4 of Figure 2.

Figure 5 is a detail view in perspective looking at the inner side of one of the side walls of the box.

Figure 6 is a detail view in perspective looking at the inner side of another of the side walls of the box.

Figure 7 is a detail view in perspective looking at the inner face of what may be either the top or the bottom of the box.

Figure 8 is a detail view in perspective of one of the hinge pins or rods.

Referring now to the drawings in detail, it will be seen that the box constituting the present invention comprises the duplicate, opposed, vertical walls 1 and the opposed, vertical walls 2. On their vertical edges the walls 1 are provided with T-heads 3 which terminate in spaced relation to the upper and

lower ends of said walls 1. The walls 1 are further provided, on their upper and lower end portions and on their inner sides with the opposed, complementary, angular flanges 4 which are arranged in pairs which terminate, at their ends, in spaced relation to the vertical edges of the walls 1; the pairs of flanges providing channels the purpose of which will be more fully hereinafter set forth.

The walls 2 have the inner side of their vertical marginal portions provided with pairs of opposed, complementary, angular flanges 5 extending from the upper to the lower ends of said walls 2 and defining channels for slidably receiving the T-heads 3 of the walls 1 for connecting the vertical walls of the box together in assembled relation.

From a consideration of Figure 3 of the drawings, it will be seen that, when the walls 1 and 2 are assembled, the upper end of one of the walls 2 is disposed slightly above the upper end of the other of the walls 2 and that the lower end of said one wall 2 is disposed above the lower end of said other of the walls 2. Formed integrally with the upper and lower ends of the walls 2 are a plurality of hinge eyes, the hinge eyes on the upper end of one of the walls 2 being disposed substantially in the vertical plane of said one wall 2 while the hinge eyes on the lower end of said one wall 2 are disposed slightly outwardly or laterally. Then, the hinge eyes on the upper end of the other of the walls 2 are disposed slightly outwardly or laterally while the hinge eyes on the lower end of said other wall 2 are disposed substantially in the vertical plane of said other wall 2.

Formed integrally with the upper and lower ends of the walls 2 are a plurality of hinge eyes, the hinge eyes on the upper end of one of the walls 2 being disposed substantially in the vertical plane of said one wall 2 while the hinge eyes on the lower end of said one wall 2 are disposed slightly outwardly or laterally. Then, the hinge eyes on the upper end of the other of the walls 2 are disposed slightly outwardly or laterally while the hinge eyes on the lower end of said other wall 2 are disposed substantially in the vertical plane of said other wall 2. This, also is illustrated to advantage in Figure 3 of the drawings.

From a consideration of Figure 3 it will be seen that one of the hinge pins to be presently described at the top of the box is disposed substantially in the vertical plane of one of the walls 2 while the other pin at the top of the box is disposed outwardly of the vertical plane of the corresponding wall 2. The same arrangement, in reversed order, is provided at the lower end of the box. The hinge eyes on the upper and lower ends of the walls 2 are designated by the reference numerals 6 and 7, respectively.

Referring now to the drawings in detail, it will be seen that the box constituting the present invention comprises the duplicate, opposed, vertical walls 1 and the opposed, vertical walls 2. On their vertical edges the walls 1 are provided with T-heads 3 which terminate in spaced relation to the upper and

The reference numeral 8 designates the top of the box and 9 is the bottom thereof. The top and bottom 8 and 9 are of duplicate construction and the detailed description of one will, therefore, suffice for both. The top 8 is provided, on a pair of its marginal edges, with the T-heads 10 for slidable insertion in the channels defined by the flanges 4 on the upper end portions of the walls 1. The top 8 is mounted in position by engaging the T-heads 10 in said upper channels of the walls 1 over the upper end of the lowermost wall 2. On one edge the top 8 is provided with the upturned hinge eyes 11 for alignment with the hinge eyes 6 on the upper end of the uppermost wall 2. On its other edge which is free of the T-heads 10 the top 8 is provided with the downturned hinge eyes 12 for alignment with the outwardly disposed hinge eyes on the upper end of the lower wall 2.

20 The bottom 9 is reversed with respect to the top 8 and is mounted in position by sliding the same in the opposite direction beneath the lower end of the uppermost wall 2 until the hinge eyes thereon register with the hinge eyes 7 on the lower ends of the walls 2.

25 Hinge pins or rods 13 are then inserted through the aligned eyes of the vertical walls 2 and the top and bottom 8 and 9, respectively, of the box and said box is thus secured together in assembled position. At one end the hinge pins or rods 13 terminate in the angular portions 14 having an eye or loop 15 on their free ends and the other end portions of the hinge pins or rods are apertured for the passage of a cotter key 16 for securing the hinge pins or rods in position.

30 It is believed that the many advantages of a knockdown box constructed in accordance with the present invention will be readily understood, and although the preferred embodiment of the invention is as illustrated and described, it is to be understood that changes in the details of construction and in the combination and arrangement of parts may be resorted to which will fall within the scope of the invention as claimed.

35 What is claimed is:—

1. A knockdown box comprising a pair of 40 duplicate, opposed vertical walls, T-heads on the vertical edges of said duplicate vertical walls terminating in spaced relation to the upper and lower ends thereof, pairs of angular, complementary flanges on the inner sides 45 of the upper and lower end portions of said duplicate walls defining channels, another pair of opposed, vertical walls, pairs of angular, complementary flanges on the inner sides of the vertical marginal portions of the second named walls for slidably receiving the 50 T-heads for detachably connecting the walls together in assembled relation, the upper and lower ends of one of the second named walls being disposed above the horizontal plane of the corresponding ends of the other second 55 named wall, a top, T-heads on certain of the edges of the top slidably engageable in the uppermost of the first named channels, said top being engageable in its respective channels over the upper ends of said other of the second named walls, a bottom, T-heads on certain of the edges of the bottom slidably engageable in the lowermost of the first named channels, said bottom being engageable in its respective channels under the lower end 60 of said one second named wall and means for detachably securing the top and bottom in position.

65 named wall, a top, T-heads on certain of the edges of the top slidably engageable in the uppermost of the first named channels, said top being engageable in its respective channels over the upper ends of said other of the second named walls, a bottom, T-heads on certain of the edges of the bottom slidably engageable in the lowermost of the first named channels, said bottom being engageable in its respective channels under the lower end 70 of said one second named wall and means for detachably securing the top and bottom in position.

75 2. A knockdown box comprising a pair of 80 duplicate, opposed vertical walls, T-heads on the vertical edges of said duplicate vertical walls terminating in spaced relation to the upper and lower ends thereof, pairs of angular, complementary flanges on the inner sides of the upper and lower end portions of said 85 duplicate walls defining channels, another pair of opposed, vertical walls, pairs of angular, complementary flanges on the inner sides of the vertical marginal portions of the second named walls for slidably receiving the 90 T-heads for detachably connecting the walls together in assembled relation, the upper and lower ends of one of the second named walls being disposed above the horizontal plane of the corresponding ends of the other 95 second named wall, a top, T-heads on certain of the edges of the top slidably engageable in the uppermost of the first named channels, said top being engageable in its respective channels over the upper ends of said other of the second named walls, a bottom, T-heads on certain of the edges of the bottom slidably engageable in the lowermost of the first named channels, said bottom being engageable in its respective channels under the lower end 100 of said one second named wall, and means for detachably securing the top and bottom in position, said means comprising aligned eyes on the upper and lower ends of the second named walls and on the adjacent edges of the top and the bottom, and pins extending through the aligned eyes.

105 In testimony whereof I affix my signature.
LEONARD CHAIN.
